UNITED STATES PATENT OFFICE.

EDWARD R. SARGENT, OF NEW HAVEN, CONNECTICUT, ASSIGNOR TO THE SARGENT & COMPANY, OF SAME PLACE.

DESIGN FOR A CASKET-GRIP.

SPECIFICATION forming part of Design No. 30,535, dated April 11, 1899.

Application filed February 17, 1899. Serial No. 705,894. Term of patent 14 years.

To all whom it may concern:

Be it known that I, EDWARD R. SARGENT, of the city and county of New Haven, in the State of Connecticut, have invented a new 5 Design for Casket-Grips, of which the following is a full, clear, and exact description, when taken in connection with the drawings, which form a part thereof, and in which—

Figure 1 is a top view of a casket-grip embodying my design; Fig. 2, a side view; Fig. 3, a reverse view from that shown in Fig. 2, and Fig. 4 a transverse section on lines 4 4 of Fig. 3.

In all figures similar letters of reference 15 represent like parts.

This invention relates to a design for casket-grips; and it consists in a configuration hereinafter described, and shown in the above referred to drawings.

20 The grip consists of a hollow plate (designated by the letter A) which is substantially angular in cross-section, Fig. 4, the side or surface C being curved and the side D sub-

stantially flat. The surface C is transversely in veeted, as shown in Figs. 1 and 3, and presents four scallops extending transversely across the surface from the meeting line E of the two surfaces C and D to substantially the outer edge F of the surface C. Extending outwardly from the edge F of the surface C 30 and also from the edge G of the surface D is a flat flange B.

Having now described my design, what I claim, and desire to secure by Letters Patent, is—

35 The design for a casket-grip as herein shown and described.

In testimony whereof I have signed this specification, in the presence of two subscribing witnesses, at New Haven, in the county 40 of New Haven and State of Connecticut, this 4th day of February, 1899.

EDWARD R. SARGENT.

Witnesses:

WILLIAM S. COOKE,
CHARLES L. BALDWIN.
